UNITED STATES PATENT OFFICE.

DANIEL HOGAN, OF INSTANTER, PENNSYLVANIA.

EXCAVATING AND DREDGING MACHINE.

No. 907,361.

Specification of Letters Patent.

Patented Dec. 22, 1908.

Application filed July 1, 1908. Serial No. 441,360.

To all whom it may concern:

Be it known that I, DANIEL HOGAN, a citizen of the United States, and a resident of Instanter, in the county of Elk and State of Pennsylvania, have invented certain new and useful Improvements in Excavating and Dredging Machines, of which the following is a specification.

My invention relates to apparatus for excavating, and it consists of a certain base frame and a carrying frame movably supported thereon and provided with guides for the frame of a reciprocating cutter device, and for the frame of a movable excavator comprising a chain of buckets, together with certain details of construction, all as set forth hereinafter and illustrated in the accompanying drawing, in which—

Figure 1 is a sectional elevation of my improved apparatus, showing the main parts of the same; Fig. 2 is a sectional view on the line 2—2 of Fig. 3; Fig. 3 is a section on the line 3—3, Fig. 1; Fig. 4 is a longitudinal section showing mainly another part of the frame and supporting structure; Fig. 5 is a plan; and Fig. 6 is a detail view of a portion of the upper end of the excavator.

The bed-frame A of the machine is supported by suitable wheels B, and may be of any form and proportions required for the purposes of the apparatus, and upon this bed-frame is supported, so as to slide longitudinally, a carrier frame C to which the working parts of the apparatus are connected, including the boiler D and engine E, which may be of any suitable form and character. As shown, the engine E is a reciprocating, reversible steam engine, but a motor propelled by air or gas or electricity may be substituted wherever it is found advisable.

The carrier frame C supports at one end an elevated frame structure F which supports a motor M of any suitable character, a steam cylinder supplied with motor fluid from the generator D, by connections that will be hereinafter described, being shown; and the said structure F also supports a vertically sliding frame G, guided between vertical guides 1, 1, and capable of being raised and lowered by means of a cable 2 passing over guide pulleys 3, to a drum 4, which may be rotated from the engine E to raise and lower the frame G. The motor M is also carried by a sliding frame H, which slides vertically between guides 8, 8, but so as to

be capable of a lateral motion also, as fully set forth hereinafter.

The frame G supports an endless line of carrier or excavating buckets I, and in order that the carrier belt which passes over guide pulleys 9, 9, may be maintained sufficiently taut, the frame consists of side pieces each of which is divided into two parts, one of the parts 10, Fig. 1, carrying the upper guide pulley and being supported to swing upon the shaft of the lower pulley to and from the horizontal portion of the other part 12, and a guide blade 13 is pivoted to the upper end of the part 10 and extends into a socket in the part 12, and has a threaded socket to receive the horizontal screw 14, which rotates at the other end in a bearing on the frame, and which may be turned by means of a socketed collar 14^a so as to set the blade 13 in and out and properly tighten the belt.

The shaft of one of the rollers 9 is a driving shaft. For instance, the shaft extends through a vertical slot in the frame F and carries a gear 16 which meshes with a gear 17, sliding upon a shaft 18 which is feathered so that the gear 17 will turn with the shaft while sliding thereon in proper relation to the gear 16. The shaft 18 has a bevel gear 19 at its lower end which is engaged by a similar gear 19^a at one end of a shaft 20 which extends longitudinally of the machine and is adapted to be driven from the engine E. To the frame F, at the rear of the excavator, is jointed the frame supporting a suitable conveyor J.

The frame H not only supports the motor M, but also the carrier bar or frame K for a series of cutters L, which are reciprocated vertically by the action of the motor. As shown rod or stem 21 of the motor piston extends through the top of the frame K, which is guided to slide vertically in the frame H, and the shank of each cutter L is connected to a link 23 which is threaded at the upper end and passes through a cross bar of the frame K, with nuts above and below the same so that each blade may be properly adjusted in respect to the frame and then secured, and so that it may be readily removed and replaced, when desired, by simply detaching the connecting bolt 24.

Each of the side cutters L is L-shaped in cross-section so as to cut the sides of the opening, and the frame H is supported by a cable 5 passing over pulleys 6 to a drum 7, being

The parts are so arranged, as shown, that the lower part of the excavating frame directs the excavating buckets to a point adjacent to the point where the cutters operate and so as to thereby take up the excavated or loosened material as fast as the same becomes detached by means of the cutters.

The action of the motor M reciprocates all 10 the cutters vertically and as the excavation proceeds the carrier frame is carried downward so that the relation of the motor and the cutters is preserved at all times whatever may be the extent to which the cutters penetrate below the surface, and the excavator or carrier is also fed downward, as required, so as to maintain its proper relation to the cutters. By use of vertically reciprocating cutters I am enabled to effect the desired 15 excavation without the necessity of carrying any extended or cumbersome framework (or cutters of large dimensions) downward below the surface and in front of the elevator or excavator chain, and am thus enabled to 20 bring the latter in closer proximity to the cutters than is practicable where rotating cutters or frames carrying cutters below the surface are employed. The character of cutters shown also has the advantage of 25 being readily operated by the engine or motor from above the surface; of being exceedingly simple in construction, and readily removed, repaired and replaced.

In operating upon some classes of earth, 30 as, for instance, where it is solid and waxy in character, it requires a great deal of power after driving a cutter downward into the material to draw the cutter outward, and in order to properly loosen the cutters after 35 they have passed down I impart a lateral vibration to the cutters by laterally vibrating the frame which supports the same, and they are thus loosened after penetrating the earth and can be raised without the adhesion 40 which would otherwise result. Any suitable means may be employed for thus vibrating the cutter carrying frame. As shown there are two eccentrics 26, 26, one mounted on the shaft 20 by which the excavator is driven and 45 the other similarly mounted on a shaft 20' extending parallel to the shaft 20 on the opposite side of the frame H. Said shafts 20, 20' are connected by a chain 20^a extending about sprockets 26' secured to the shafts so 50 that the shaft 20' is positively driven from the shaft 20. The eccentrics 26 are so arranged as to swing the cutter frame first in one direction and then in the other. This vibration of the cutters not only has the effect 55 before described, but also tends generally to aid in loosening the earth and facilitating the excavation.

Steam for actuating the cutter engine M is supplied through flexible ducts 30, 31, 31' 60 which are connected with a pipe 32 leading

from the boiler D. The duct 30 is connected directly with the pipe 32 while the ducts 31, 31' are connected with a branch 32'. The pipe 30 communicates with the steam chest m within which is arranged a suitable 70 slide valve adapted to be actuated by a lever k one end of which is connected, through an adjustable rod k', with the sliding cutter frame K. Cut-off valves 33, 34 are arranged respectively in the pipe 32 and branch 32', 75 and a hand lever 35 is arranged to control a valve in the pipe 32, while a similar lever 36 is adapted to actuate a valve controlling the passage of fluid to both the ducts 31, 31'. By this means the parts may be so arranged 80 that the cutters will be automatically reciprocated for any desired length of time, or each stroke or operation thereof may be controlled by manipulation of the hand lever 36. If it is desired to have the cutters 85 operate automatically, the valve 34 is closed and the valve 33 opened. By properly adjusting the hand lever 35 fluid will be permitted to pass through the duct 30 to the chest m of the motor M, and when 90 the parts are in the position shown, the valve in said chest will cause the fluid to pass into the upper part of the motor cylinder thereby depressing the frame K and cutters L. As the frame K moves downward the lever k 95 will be rocked to shift the valve in the chest m, and as the frame and cutters reach the limit of their downward movement the valve will be so moved that the fluid will enter below the piston, and thereby the frame K 100 and cutters L will be raised. This reciprocation will be continued as long as the valve controlled by the hand lever 35 is maintained in its open position.

In case it be desired that the operator 105 control each reciprocation of the cutter frame, the valve 33 is closed and that at 34 opened. By then moving the hand lever 35 to open the valve controlled thereby and by shifting the hand lever 36 the fluid will 110 be alternately admitted to the ducts 31' and 31 to reciprocate the piston in the motor M, and thereby lower and raise the frame K and cutters L.

The apparatus may be propelled from the 115 engine E through the medium of suitable gears between the engine shaft and any of the supporting wheels B. As shown, two of the supporting wheels have gear teeth 42, with which gear pinions 43, on a shaft 44, 120 which is driven by beveled gears 45, from a longitudinal shaft 46, supported to turn in bearings on the frame A, and carrying a pinion 47 which slides on and turns with the said shaft by means of a suitable feather 125 thereon. This pinion 47 gears with the driving spur wheel 48 carried by the engine shaft and which may be caused to turn therewith, or it may be detached therefrom by means of a friction clutch 49, operated 130

by a hand-lever 50. As the engine is carried by the carrier frame C and slides longitudinally in respect thereto, the pinion 47, while turning the shaft 46, can slide thereon according to the position of the upper frame.

After the apparatus is put at work it of course becomes necessary to feed the cutters forward in the direction of the arrow, Fig. 1, and this forward movement is effected without altering the position of the lower frame except after the upper frame has reached the limit of its forward travel upon the lower one. Preferably the movement of the upper frame upon the lower frame is effected through the medium of a rotating screw 51 supported to turn in bearings on the lower frame and passing through a nut 52 upon the upper frame, and the said screw 51 may be driven from the engine from time to time as required. Thus a pinion 53 on the engine shaft drives a pinion 54 on a counter-shaft 55, which carries a spur wheel 56, gearing with a spur wheel 57, which turns with but slides on the screw-shaft 51, through the medium of a suitable feather, and a friction clutch 58, operated by a hand-lever 59, serves to connect the spur wheel 53 and disconnect it from the engine shaft.

It will be seen that the chain of excavator buckets cannot only be operated in connection with the cutters to remove the cuttings, but that by elevating the cutter frame and cutters and holding the same out of operation and operating the excavator apparatus, it is possible to excavate sand and soft materials where the use of the cutters is not required, so that wherever in ditching or other operations a bed of sand or of soft material is encountered the excavator apparatus may be used alone. It will further be evident that the excavator apparatus may be used alone wherever required by dispensing with the under frame A and its wheels, and placing the other parts of the apparatus upon a scow, or suitable boat, and that as thus supported by using either the excavator alone or in connection with the cutters it is possible to operate under water advantageously for many engineering purposes. Of course where used upon a boat the carrier frame C may be shifted in respect to its supports upon the boat just the same as in connection with the lower wheel-supported frame, and thus by anchoring a boat the cutting operations may be effected over a considerable area without changing the position of the boat. It will be evident that by mounting a plurality of such apparatus upon the same scow or boat the excavating operations may be greatly extended.

It will be understood that the drawings illustrate more or less conventionally the gearing for driving the shafts 20, 20' and the winding drums 4 and 7, as any suitable gearing may be employed for such purposes.

If it is desired to use the apparatus for excavating trenches of considerable depth the machine may be mounted on a car or truck instead of on a wagon as shown, the said car or truck being operated on a suitable track in a manner similar to that in which steam shovels are commonly operated.

Without limiting myself to the precise construction and arrangement of parts shown, I claim:

1. In an excavating apparatus, the combination of a supporting or base frame, a carrier frame mounted to slide on the supporting frame, and a cutting apparatus, and an excavating apparatus both vertically adjustable upon the carrier frame.

2. In an excavating apparatus, the combination of a supporting or base frame, a carrier frame mounted to slide on the supporting frame, a cutting apparatus, an excavating apparatus vertically adjustable upon the carrier, and an engine and connections supported on the carrier frame for raising and lowering the cutters and excavators.

3. In an excavating apparatus, the combination of a supporting or base frame, a carrier frame mounted to slide on the supporting frame, a cutting apparatus, an excavating apparatus vertically adjustable upon the carrier, an engine on the carrier frame, and means for shifting the carrier frame on the base frame by the engine.

4. In an excavating apparatus, the combination of a supporting or base frame provided with supporting wheels, an engine, a carrier frame mounted to slide on the supporting frame, a cutting apparatus, an excavating apparatus vertically adjustable upon the carrier frame, and means for causing the engine to drive the wheels.

5. The combination in an excavating apparatus, of a base frame, a carrier frame sliding thereon and provided with vertical guides, a frame supported to slide on said guides, a motor carried by said frame, and cutters connected to be operated by said motor.

6. The combination, in an excavating apparatus, of a base frame, a carrier frame sliding thereon and provided with vertical guides, a frame supported to slide on said guides, a motor carried by said frame, cutters connected to be operated by said motor, a second set of guides on the said frame, an excavator frame vertically adjustable in the last said guides, and a chain of buckets carried by said frame.

7. The combination, in an excavating apparatus, of a base frame, a carrier frame sliding thereon and provided with vertical guides, a frame supported to slide on said guides, a motor carried by said frame, cutters connected to be operated by said motor, other guides on said frame, an excavator frame vertically adjustable in the last said guides, a chain of buckets carried by said

frame, and means for positively driving said chain.

8. The combination with the frame of an excavator, of vertical guides, and a frame 5 vertically adjustable on said guides, said frame supporting a chain of buckets and consisting of sections converging and pivotally connected at the bottom, with means for separating their upper ends and holding them in 10 position.

9. The combination, in an excavating apparatus, of a base frame, a carrier frame sliding thereon, guides upon the carrier frame, a motor and cutters and a frame and bucket 15 chain mounted to slide on said guides, an engine on the carrier frame, and connections for driving the bucket chain from said engine.

10. The combination, in an excavator apparatus, of a carrier frame provided with vertical guides, a chain of buckets and a frame therefor provided with guide pulleys adjustable in said guides, a vertical driving shaft supported to rotate in bearings of the carrier frame, a sliding gear on said shaft, and a gear 25 connected with one of the guide pulleys engaging the same, and an engine on the carrier frame connected to drive said vertical shaft.

11. The combination, in an excavator apparatus, of a carrier frame provided with vertical guides, a chain of buckets and a frame therefor provided with guide pulleys adjustable in said guides, a vertical driving shaft supported to rotate in bearings of the carrier frame, a sliding gear on said shaft, a gear 30 connected with one of the guide pulleys engaging the same, an engine on the carrier frame connected to drive said vertical shaft, and a drum and means for driving the said drum from said engine, and cable connection between said drum and the bucket chain frame.

12. The combination, in an excavating apparatus, of a vertically guided frame, a motor mounted thereon, and cutters guided to slide vertically and connected with the motor 45 to be reciprocated thereby.

13. The combination, in an excavator ap-

paratus, of a carrier frame, vertical guides thereon, a frame and motor thereon mounted adjustably on said guides, and cutter stems having cutters at their lower ends connected 50 to be reciprocated by said motor.

14. The combination, in an excavator apparatus, of a carrier frame, vertical guides thereon, a frame and motor thereon mounted adjustably on said guides, cutter stems having 55 cutters at their lower ends connected to be reciprocated by said motor, a control device for the motor, automatic means for shifting said device, and a supplemental hand control device.

15. The combination, in an excavating apparatus, of a vertically guided frame, a motor mounted thereon, and cutters guided to slide vertically and connected with the motor to be reciprocated thereby, and means for 60 imparting lateral movements to the cutters.

16. The combination, in an excavating apparatus, of a vertically guided frame, means for adjusting the same vertically, a motor and cutters carried by said frame, and devices for imparting a lateral reciprocation to 65 said frame.

17. The combination, in an excavating apparatus, of a vertically guided frame, a motor having a cylinder and piston and piston 70 rod, a frame connected to said piston rod, and a series of cutter stems connected with said frame and having cutters at their lower ends.

18. The combination of the cutter frame, 75 the motor connected to reciprocate said frame vertically, a series of cutter stems, a cutter at the lower end of each stem, and links each connected by a bolt to the upper end of one of the stems, and at the upper end 80 to the cutter frame.

In testimony whereof I affix my signature in presence of two witnesses.

DANIEL HOGAN.
